UNITED STATES PATENT OFFICE.

WILLIS H. CARRIER, OF ESSEX FELLS, NEW JERSEY, ASSIGNOR TO CARRIER ENGINEERING CORPORATION, OF NEWARK, NEW JERSEY.

SUBSTANCE AND PROCESS OF USING THE SAME FOR REFRIGERATING PURPOSES.

No Drawing.

Application filed March 22, 1924. Serial No. 701,230.

My invention relates to a substance and a process of using the same in refrigeration, whether for making ice, for cold storage work, for cooling water for use in conditioning air, or for other cooling purposes.

The substance known as dichloroethylene and having the formula $C_2 H_2 Cl_2$ has certain properties or characteristics which are ideal in a refrigerating medium. It has a boiling point of approximately $55^\circ C.$; it is inactive towards common metals at any temperature, either in the liquid or gaseous state, or in the presence of water; it does not volatilize appreciably at ordinary atmospheric temperatures; it will not freeze at any temperature which will be encountered. The gas is dense, being several times heavier than air and does not readily diffuse or spread, thus permitting the refrigerating apparatus to be opened up at any time without removing the liquid and without objection from fumes; the liquid will not explode or readily burn and it can be handled like water in open containers with entire safety.

I have found, however, that the commercial dichloroethylene, which has been used for refrigeration, has the objection that its boiling point is variable. The boiling point increases as the liquid is evaporated so that purging in the refrigerant and constant reduction of volume of the liquid causes a continually rising boiling point, and also causes an appreciable difference between the boiling point and the condensing point, thereby reducing the efficiency of the refrigerating machine. The reason for this is that normal commercial dichloroethylene contains two isomers; one, trans-isomer, having a boiling point of approximately $49^\circ C.$, and the other, cis-isomer, having a boiling point of approximately $60^\circ C.$. The proportion of these isomers is approximately 25 percent or 30 percent trans-isomer to 75 percent or 70 percent cis-isomer. The respective vapor pressures of these two isomers at the same temperature is about in the proportion of 1 to .54, thus in a normal mixture of the saturated vapors of the different isomers, about 65 percent will be of a trans-isomer and 35 percent will be of a cis-isomer.

This objection I have succeeded in overcoming by separating the two isomers of the commercial dichloroethylene, which

may be done, for example, by fractional distillation, and by using either of the two isomers as a refrigerant. Either of the isomers, when comparatively free of the other isomer, has a range of boiling points which is sufficiently stable for commercial purposes, regardless of the quantity evaporated. While either of the two isomers may be used as a refrigerant, it has been found less difficult to prepare the cis-isomer, which has the higher boiling point, this isomer being present in greater quantities in the commercial dichloroethylene.

In my process of refrigeration, using this new refrigerating medium, the refrigerant liquid is evaporated, preferably by the heat abstracted from the water or other medium or enclosure being cooled, and the refrigerant vapor is compressed and condensed, the liquefied and cooled refrigerant being returned to be again evaporated, this cycle of operations being continuous. Preferably, a centrifugal compressor is used which produces only a moderate difference in pressure, and the refrigerant is condensed as well as evaporated at a pressure below one atmosphere so that the entire system is under a partial vacuum. All liquefied refrigerant is immediately transferred as formed from the condenser to the evaporator, and any surplus liquid is maintained in the evaporator. Simultaneously with the return of the liquefied refrigerant from the condenser, the residual dense refrigerant vapor, together with any non-condensable gas or air that may be present are withdrawn from the condenser, and after compressing and condensing the vapor to separate it from the non-condensable gas, the condensate is returned to the evaporator at the temperature level of the evaporator. This enables the boiling point in the evaporator and the condensing point in the condenser to be maintained more nearly the same, since if the liquid is allowed to collect in the condenser, there would be an accumulation of the less volatile portion in the condenser while the more volatile portion would be removed.

I claim as my invention:

1. A refrigerating process which comprises evaporating a refrigerant consisting substantially of only one of the isomers of dichloroethylene, compressing and condensing the resultant vapor to liquefy the same

and returning the liquefied dichloroethylene to be again vaporized.

5 2. A refrigerating process which comprises evaporating a refrigerating medium consisting substantially of the cis-isomer of dichloroethylene, compressing and condensing the resultant vapor to liquefy the same and returning the liquefied refrigerating medium to be again vaporized.

10 3. A process of refrigeration which comprises evaporating, compressing and condensing a refrigerating medium having one only of the isomers of dichloroethylene under a pressure at all times not materially greater than one atmosphere.

15 4. A process of refrigeration which comprises evaporating, compressing and condensing a refrigerating medium having one only of the isomers of dichloroethylene all in a partial vacuum.

20 5. A process of refrigeration which comprises evaporating, compressing by centrifugal action, and then condensing a refrigerating medium having one only of the 25 isomers of dichloroethylene under a pressure at all times not materially greater than one atmosphere.

30 6. A process of refrigeration which comprises evaporating, compressing by centrifugal action, and condensing a refrigerating medium having one only of the isomers of dichloroethylene all in a partial vacuum.

35 7. The process of refrigeration which comprises evaporating a refrigerating medium having one only of the isomers of dichloroethylene at a pressure below atmospheric pressure, compressing the vapor thus formed, and condensing the compressed vapor at a pressure not materially greater than approximately atmospheric pressure.

40 8. A refrigerating device, comprising an evaporator, a compressor and a condenser connected together in a closed circulatory system, and a quantity of one only of the 45 isomers of dichloroethylene in said system, the pressure in said evaporator being less than atmospheric pressure.

45 9. A refrigerating device comprising an evaporator, a compressor and a condenser connected together in a closed circulatory system, and a quantity of one only of the isomers of dichloroethylene in said system, the pressure in said evaporator being less than atmospheric pressure, and pressure in said condenser not materially greater than approximately atmospheric pressure.

50 10. A refrigerating device comprising an evaporator, a compressor and a condenser connected together in a closed circulatory system, and a quantity of only one of the isomers of dichloroethylene in said system, the pressure in said evaporator being less than atmospheric pressure, and pressure in said condenser being less than atmospheric.

55 11. A refrigerating device having an evap-

70 evaporator, centrifugal compressor and condenser connected in a closed circulatory system, and a refrigerating medium having one only of the isomers of dichloroethylene as the refrigerating medium.

75 12. A refrigerating device including an evaporator, centrifugal compressor and condenser connected in a closed circulatory system and containing therein a refrigerating medium having one only of the isomers of dichloroethylene, the differences in internal pressures between the compressor, condenser and evaporator being relatively small.

80 13. A process of refrigeration which comprises evaporating, compressing by centrifugal action, and then condensing cis-isomers of dichloroethylene under a pressure at all times not materially greater than one atmosphere.

85 14. A process of refrigeration which comprises evaporating, compressing by centrifugal action, and condensing cis-isomers of dichloroethylene all in a partial vacuum.

90 15. A process of refrigeration which comprises evaporating, compressing and condensing cis-isomers of dichloroethylene under a pressure at all times not materially greater than one atmosphere.

95 16. A process of refrigeration which comprises evaporating, compressing and condensing cis-isomers of dichloroethylene all in a partial vacuum.

100 17. The process of refrigeration which comprises evaporating a refrigerating medium having the cis-isomers only of dichloroethylene at a pressure below atmospheric pressure, compressing the vapor thus formed, and condensing the compressed vapor at a pressure not materially greater than approximately atmospheric pressure.

105 18. A refrigerating device, comprising an evaporator, a compressor and a condenser connected together in a closed circulatory system, and a quantity of cis-isomers of dichloroethylene in said system, the pressure in said evaporator being less than atmospheric pressure.

110 19. A refrigerating device, comprising an evaporator, a compressor and a condenser connected together in a closed circulatory system, and a quantity of cis-isomers of dichloroethylene in said system, the pressure in said evaporator being less than atmospheric pressure, and pressure in said condenser not materially greater than approximately atmospheric pressure.

115 20. A refrigerating device comprising an evaporator, a compressor and a condenser connected together in a closed circulatory system, and a quantity of cis-isomers of dichloroethylene in said system, the pressure in said evaporator being less than atmospheric pressure, and the pressure in said condenser being less than atmospheric.

120 21. A refrigerating device having an evap-

orator, centrifugal compressor and condenser connected in series, and cis-isomers of dichloroethylene as the refrigerating medium.

5 22. A refrigerating device including an evaporator, centrifugal compressor and condenser connected in a closed circulatory

system, and containing therein cis-isomers of dichloroethylene as the refrigerating medium, the differences in internal pressures 10 between the compressor, condenser and evaporator being relatively small.
